APPARATUS FOR SEPARATING MATERIALS
OF DIFFERENT SPECIFIC WEIGHTS

Rudolf Maier, Stuttgart, Germany

Application July 30, 1937, Serial No. 156,598
In Germany July 30, 1936

4 Claims. (Cl. 209—144)

The invention relates to apparatus to eliminate from a gas by means of centrifugal force materials of different specific weights floating in the gas or being mixed up with it, or to separate these materials from each other.

Separating by centrifugal force is the most simple and the cheapest of all means that have been employed for the above purpose. But this method of separating materials has not been successful when applied to materials with very little difference in their specific weights or of an extreme dispersity although theoretically there is no reason to suppose, that centrifugal force should not be able to be used to that end. The necessity however to eliminate for instance dusts of extreme dispersity from gases has led to other means being tried, such as electric dust collectors. But these and most of the other separating devices are very expensive and voluminous and do not meet all those requirements which have often to be satisfied in modern plants.

The process of the present invention makes it possible to eliminate from gases materials of unlimited dispersity or separate them from each other, even if there is very little difference in their specific weights, by means of installations which require very little space and small initial and running cost. The process may even be applied to separate by centrifugal force gases of different density out of a mixture, such as carbonic oxide out of lighting gas.

The various objects and features of the invention will be apparent from a consideration of the following description and the appended drawing 35 wherein an exemplary embodiment of the invention is disclosed.

The single figure of the drawing is an axial sectional view illustrating a rotor for separating suspended materials of different specific weights. A hollow cylinder 1a, adapted for fast rotation, is immersed in the mixture to be dedusted or separated. Its thick wall is perforated by many channels 2a. One end of the cylinder is closed and the opposite end extends through a housing 3a provided with a stuffing box 3b and a second stuffing box 3c. At the end of the cylinder there is a coupling 4a for a motor 4b. A pipe 5a connects the housing 3a with a suction pump 5b which may be regulated by well-known devices. Output and speed of the motor must be adjustable within a wide range. It is supposed that the cylinder rotates in the open air or in a wide channel filled with gas and dust.

The gas mixture to be de-dusted is forced along the channels in the rotating cylinder with any

desired speed in the direction of the arrows. All particles must now take part for some time in the rotation of the cylinder 1a. Thus they are exposed for some time to the influence of a field of centrifugal force driving them outwards off the cylinder, or in an opposite direction to the flow which is taking them to the cylinder axis. The field of centrifugal force extends not only to the interior of the cylinder and to the channels 2a, but also beyond its exterior surface as far as its rotation creates a noticeable following wind. It should be observed that the cylinder must not have any projecting parts, which would have an effect similar to that of propeller or ventilator vanes pressing away the gas in front of it. The cylinder will transmit its rotation to the gas surrounding it by friction in such manner as to form a purely rotating laminar flow. This flow creates a rotating layer of gas around the cylinder which according to its nature as a following wind is of a very stable character.

The duration of the action of the field of centrifugal force on the gas and the particles flowing with it may be regulated from fractions of seconds up to any desired period by adjusting the speed of the suction pump 5b. The extent and strength of the field of centrifugal force through which all particles must pass, are also determinable within wide limits. For instance that part of the field of centrifugal force which is acting in the interior of the cylinder may be made long or short by employing a cylinder of corresponding thickness or by inserting into it pipes of corresponding lengths. The part of the field of centrifugal force which is created outside by the following wind, may also be determined by an adequate enveloping of the cylinder by means of a casing 6a and a corresponding speed of rotation. The strength of the field of centrifugal force also may be regulated from zero up to very high values, because it is possible to give such rotors peripheral speeds of hundreds of metres per second.

It is therefore possible to expose all particles of the gas mixture to a determinable and adjustable field of centrifugal force during a determinable time and over a determinable length of way, the three factors being determinable and adjustable independently of one another. The counter action of centrifugal force and suction force makes it possible to influence very exactly the process of separation of the gas and the particles flowing with it in such manner that the gas sucked off the mixture will take with it only well-defined parts of the finest or lightest components.

It is therefore possible by means of the apparatus described to augment quite considerably the separating effect of the centrifugal force in comparison with the prior art.

5 The invention therefore consists in immersing into the gas mixture to be treated a rotor adapted for rotation at high speed, the rotation of which creates in its interior and in its vicinity a strong and regulable field of centrifugal force, and in 10 conducting the mixture with determinable and regulable speed through that field of centrifugal force opposite to the direction of the centrifugal force. The rotating cylinder acts chiefly as a means for creating the field of centrifugal force, 15 but not as a means for collecting the dust out of the gas mixture and throwing it off in the manner of many devices of the prior art. These devices are usually provided with vanes as used on ventilators or blades, or rotating combs and 20 brushes, and it is these parts themselves—not a field of centrifugal force created by them within a laminar rotating layer of gas—which form the chief obstacle opposed to the flow and which retain the particles not desired. A rotating body 25 acting as dust collector cannot in addition be used for sorting out, because it will eliminate particles regardless of their size. The rotating cylinder or other parts used in the present invention are therefore designed in such manner 30 as to reduce their capacity of catching dust particles and the like as much as possible.

In the arrangement described the speed of rotation of the gas mixture is highest immediately on the surface of the rotor. This is in contrast to the well-known cyclone apparatus. The flow in such devices is more disturbed as it approaches the axis. This is the consequence of the whirlwinds being roused in such centrifugal separators, and which chiefly prevent the separation 40 of the finer particles moving along a slowest speed. In the apparatus according to the invention it is just the centre of the mixture which is led in the best manner.

The number and size of the perforations may 45 vary within wide limits, as well as the shape of the rotor and its size in relation to the container in which it rotates and also the depth up to which the rotor is immersed into the mixture to be treated. The perforated rotor allows of a 50 continuous run of the apparatus for any length of time, choking of the channels being avoided by the constant circulation or by flinging it off by an occasional acceleration of the circulation.

The shape of the container in which the cylinder is arranged may be chosen at liberty. In 55 many cases there is no need at all for a container, as when extracting one of the components of atmospheric air.

It does not matter much in which direction the 60 mixture enters the container inside which the rotor revolves.

The process and apparatus described permit large quantities of gas to be de-dusted or sorted. The invention also enables gases of different 65 density to be separated. The possibility of separating gases by centrifugal force is well-known in the art. But by the process and the apparatus of the present invention, a suitable arrangement has been created by means of which gases may 70 be separated mechanically in any quantities desired, because the effect of the centrifugal force may be prolonged at liberty as far as duration is concerned and the efficiency may be regulated very precisely. The layer of air formed round the 75 revolving rotor is very stable. Its stability in-

creases the more it approaches the rotor wall or enters the rotor through the material out of which it consists or on account of its particular shape. By means of an adequate raising of the centrifugal effect and a sufficiently long duration 5 of this effect the separation takes place inside this gas layer. The quantities passing the channels in the rotor is regulated according as to whether a full or partial separation is desired. In the case of gases—as pointed out already—the 10 condition of the surface of the rotor is of great importance for the formation of the gas layer. The same is the case with the physical or chemical affinity of the material of the rotor to the different gases, for example a platinum plated 15 surface may be favorable for separating hydrogen.

I claim:

1. Apparatus for separating one constituent from a gaseous mixture by centrifugal force comprising, a hollow rotor of substantially cylindrical shape having inside and outside substantially smooth surfaces, a closed end, the wall of said rotor being relatively thick and apertures in the wall, a gas-duct connecting the hollow inside with 20 a container, means for rotating said rotor around its axis at high speed creating and stabilizing a rotating laminar flow of the gaseous mixture around the wall, said flow forming a field of 25 centrifugal force, and means to suck gas off said 30 field through said apertures into said hollow inside and further through said gas duct into said container.

2. Apparatus for separating one constituent from a gaseous mixture by centrifugal force comprising, a smooth cylinder having a relatively thick wall provided with radially extending channels, a housing and means creating suction therein, means for rotating said cylinder around the axis thereof at a relatively high speed so as to 40 create a rotating laminar flow of the gaseous mixture around the wall of the cylinder by friction between the mixture and the wall of the cylinder, and means connecting the interior of 45 said cylinder with the housing so as to suck a part of the mixture from the interior of the cylinder without disturbing the laminar flow of the gaseous mixture.

3. Apparatus for separating one constituent from a gaseous mixture by centrifugal force comprising a cylinder having a relatively thick smooth wall and a closed end, the wall of said cylinder having openings therein providing relatively long channels through the wall of the cylinder, a tubular member extending axially from 55 the cylinder and having openings therein, a casing surrounding said tubular member provided with bearings for rotatably supporting the cylinder, means for driving said cylinder at a relatively high speed so that the friction of the 60 smooth wall with the gaseous mixture will create a rotating laminar flow of the gaseous mixture around the wall of the cylinder, and suction means for drawing a part of the gaseous mixture into said housing without disturbing the flow of 65 the gaseous mixture adjacent the cylinder wall.

4. Apparatus for separating one constituent from a gaseous mixture by centrifugal force comprising a cylinder having a relatively thick smooth wall and a closed end, the wall of said cylinder 70 having openings therein providing relatively long channels through the wall of the cylinder, a tubular member extending axially from the cylinder and having openings therein, a casing surrounding said tubular member provided with bearings 75

for rotatably supporting the cylinder, means for driving said cylinder at a relatively high speed so that the friction of the smooth wall with the gaseous mixture will create a rotating laminar flow of the gaseous mixture around the wall of the cylinder, suction means for drawing a part of the gaseous mixture into said housing

without disturbing the flow of the gaseous mixture adjacent the cylinder wall, and a casing of larger cross-sectional area than said cylinder for supplying the gaseous mixture to the exterior of said cylinder.

RUDOLF MAIER.
